(57) **CLAIM**

We claim the ornamental design of a surface-mount electrical connector, as shown and described.

DESCRIPTION

FIG. 1 is a perspective view of a first and a second variant of the electrical connector according to the present design; FIGS. 2 and 6 are side elevational views of the first variant of the electrical connector according to the present design; FIG. 3 is a front elevational view of the first and second variant of the electrical connector according to the present design;

FIG. 4 is a top plan view of the first and second variant of the electrical connector according to the present design; FIG. 5 is a bottom plan view of the first and second variant of the electrical connector according to the present design; FIG. 7 is a rear elevational view of the first and second variant of the electrical connector according to the present design; and,

FIGS. 8 and 9 are side elevational views of the second variant of the electrical connector according to the present design.
